UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP CAR.

Application filed February 9, 1924. Serial No. 691,830.

To all whom it may concern:

Be it known that I, ARGYLE CAMPBELL, a citizen of the United States, residing at Chicago, in the county of Cook and State 5 of Illinois, have invented a certain new and useful Improvement in Dump Cars, of which the following is a full, clear, concise, and exact description, reference being had to the accompanying drawings, forming a 10 part of this specification.

This invention relates to improvements in dump cars.

An object of this invention is to provide an improved car construction which will 15 provide for increased efficiency and safety in the operation of dump cars.

More specifically, this invention relates to improvements in a door operating mechanism adapted for pivoted drop doors and 20 wherein is employed a slidable latch or lock carried by the door adapted to project over and rest upon the shaft when the door is in closed position, and it is a particular object of this invention to provide an improved 25 mounting for this type of a latch assuring greater stability and security of operation than is now possible with existing types.

Another object of the invention is to provide an improved means of rotating a dump 30 door operating shaft.

The invention furthermore consists in the improvements in the parts and devices and in the novel combination of the parts and devices herein shown, described and made 35 the subject matter of claim.

In the drawings forming a part of this specification, Figure 1 is a plan view of a portion of a drop bottom freight car, showing my improvements in connection therewith. Figure 2 is a longitudinal sectional view taken on a line corresponding to a line 2-2 of Figure 1. Figure 3 is a fragmental side view of a portion of the car illustrating the shaft rotating mechanism in elevation. 40 Figure 4 is a vertical, sectional view taken on a line corresponding substantially to a line 4-4 of Figure 1. Figure 5 is a vertical, sectional view of the shaft rotating mechanism, corresponding substantially to the line 5-5 of Figure 3. Figure 6 is a vertical, sectional view through the latch mechanism corresponding substantially to the line 6-6 of Figure 1. Figure 7 is a vertical, sectional view through the latch mechanism corresponding substantially to the line 7-7 of

Figure 1. Figure 8 is a plan view of a portion of a drop bottom car illustrating a different embodiment of the invention. Figure 9 is a vertical, sectional view taken longitudinally of the car and on a line corresponding substantially to line 9-9 of Figure 8.

Referring first to the construction shown in Figs. 1 to 7 inclusive, 10 denotes one of the side walls of the car, 11 one of the transverse crossbeams, 12 one of the upwardly extending side stakes of the car, 13-13 fixed floor sections disposed to either side of a dumping opening, 14 a longitudinally extending floor section disposed at the edge 70 of the door, and 15 a pivoted floor door arranged to be substantially flush with the floor of the car when the door is in closed position. Said door 15 is pivoted along its inner edge by means of hinge straps 16 and hinge pins 17 to hinge butts 18 riveted or otherwise secured to one of the crossbeams 11 of the car. The edges of the door are preferably flanged as indicated at 19.

Although in the drawings I have illustrated only a portion of a floor door of a car and only the immediately adjacent portions of the car, it will be understood by those skilled in the art that there are preferably two doors disposed on axes extending transversely of the car, and respectively located to either side of the longitudinal center of the car and adapted to be operated in unison from a common operating shaft. Latches and associated co-operating parts will preferably be used, two for each door, but inasmuch as the operation of all these mechanisms would be similar, I deem it only necessary to illustrate and describe in detail one of them.

In carrying out my invention I employ an operating shaft 20 which extends parallel to the free edges of each set of pivoted doors, although it will be evident that a separate operating shaft may be provided for said door disposed parallel to the free edge thereof. The operating shaft is located beyond the curved path of movement of the free edges of the doors so that said edges clear the shafts and associated parts. Said shaft 20 is also located in a plane somewhat below the plane of the door with which it is associated. In actual practice, in a car such as indicated in the drawings, said shaft 20 will pass through the center sills of the car 110

- (not here shown), and will be there mounted in suitable bearings. At each side of the car the shaft is mounted in a suitable bearing 21 which is secured to the corresponding bottom chord 22 of the side wall, said chord 22 preferably consisting of an angle member having one flange 23 disposed in a vertical plane, and another flange 24 disposed in a horizontal plane. In cars of this type it is customary to extend the side wall of the car below the floor level of the car, as shown in Figure 4, thereby providing additional depth for the said side.
- Mounted on each pivoted door, (there preferably being two sets for each door) is a channel shaped member 25, to which the corresponding strap is secured, the member 25 having the web 26 thereof secured to the door and having spaced flanges 27-27 depending therefrom, said members 25 being located on the under side of the door. Near the free edge of the door there is provided an additional member 28 having a horizontal web 29 spaced away from the door plate and two vertical webs 30-30 each lying against the outer side of the flanges 27-27 of the hinge member, thereby completing a box-shaped receptacle open at its outer and inner ends within which a slideable latch, designated generally by the reference character A, is mounted. The outer end of said latch A, when the door is in closed position, rests directly over the shaft 20 and is supported thereby, and the inner end of the latch is supported on a roller bearing 31 which is pivotally mounted on a trunnion 32 fixed relatively to the housing member 28. The ends of the roller bearing 31 are of reduced diameter as indicated at 33 in order to permit the side flanges 34 of the latch member A to straddle said roller, the side flanges 34 serving to give additional strength to the latch member by increasing the depth thereof. The rear end of the latch is formed with a downwardly projecting portion 35 which operates to limit the outward movement of the latch in the housing through engagement of the same with the roller. The upper surface of the latch member A is provided with two longitudinally extending parallel grooves 36 which constitute runways for ball bearings 37 which are interposed between the latch and the door and being bodily movable provide for easy movement of the latch member. Inasmuch as the intermediate bearing is called upon to sustain the sum of the individual loads at the respective end supports of the latch it is evident that the liability to bind is greater at the intermediate bearing and the disposition of a rolling antifriction bearing at this point provides for easy movement of the latch under load. On the other hand the load at the inner end of the latch is comparatively small and the use of a fixed roller at this point

provides for greater stability and also permits the use of a shorter housing than is possible when such end bearing member is bodily movable.

An opening 38 is provided in the lower horizontal wall of the housing through which the roller 31 is inserted and when the same is in operative position and with the trunnion 32 in place the latch member A is prevented from pulling out. At its outer end the latch member is formed of restricted width for a limited distance as shown at 39 and a block 40, forming a terminal link of the connection between the shaft and the latch is pivoted thereto, the pivotal connection being shown at 41 and as will be noted, said pivotal connection is located directly over the axis of the operating shaft when the parts are in closed position. To the outer end of the block 40 is pivotally connected a link 42 and the latter is in turn pivotally connected at 43 to a link 44. Pivotally attached to the opposite end of said link 44 is a link 45 which in turn is pivotally connected as indicated at 46 to the arm 47 formed integrally with a hub casting 48 rigid with the shaft 20. Said hub casting 48 is formed on its upper face, when the parts are in position as in Fig. 2, with a flat surface 49 on which the locking block 40 bears as shown in the drawing. In addition, said hub casting 48 is provided with an up-standing shoulder 50 which is arranged to engage a shoulder 51 formed on the locking block 40 for the purpose hereinafter described.

The shaft rotating mechanism is disposed adjacent the side wall of the car and a preferred construction includes a ratchet wheel 52 rigidly secured to the shaft by means of a squared portion 53 corresponding to the shape of the shaft. A recess is formed in the ratchet as indicated at 54 and a pin 55 inserted through the shaft to prevent outward movement of the ratchet. Rotatable with respect to the ratchet wheel 52, there is provided rotatable mechanism designated broadly by the reference character B. Said mechanism consists of inner wall 56 and outer wall 57 disposed respectively to either side of the ratchet wheel and united together by means of rivets 58, said rivets 58 are encircled by means of ferrules 59 which effectively space the said inner and outer wall. A squared portion 60 is formed integrally with the outer wall and is adapted to receive the end of an operating wrench whereby the mechanism is rotated; said squared portion is perforated and the end of the shaft 20 is formed with a circular portion 61 which extends within the perforation formed in the squared portion 60 thereby producing a very stable mechanism. A pawl 62 is pivotally mounted on one of the ferrules and by means of this pawl operative

engagement is established between the rotatable member B and the ratchet wheel 52. Co-operable with the ratchet wheel 52 is a pawl 63 pivotally mounted on the bracket 5 21 adapted to engage the said ratchet wheel 52 to lock the same during the raising operation of the door and also prevent the shaft from turning when the doors are in closed position. Co-operable with the said pawl 63 10 is a safety cam 64 to positively lock the same in closed position.

The fixed floor portion adjacent the free edge of the door is suitably rigidified by means of an angle member 65 riveted to the 15 floor section and having a flange 66 extended downwardly to a point below the latch member A, and in order to allow the latter to pass over the shaft the said depending flange has a portion thereof formed of restricted 20 depth by bending a portion of the same at right angles to the main body of the flange, as shown at 67, and thereby forming a channel shape out of the angle at this point.

The operation is as follows: Assuming the 25 parts in the position shown in Figs. 1 and 2, the operator after first disengaging the locking cam 64 from the pawl 63 and swinging the latter free of the ratchet wheel 52 and then rotating the pawl 62 in the direction indicated by the arrow to the position shown in dotted lines, rotates the mechanism B in a clockwise direction by engagement with the squared section. As the mechanism B is rotated in a clockwise direction the shaft 30 20 will rotate in unison therewith due to the cooperating engagement between the pawl 62 and the ratchet wheel 52. As the shaft is thus rotated, the shoulder 50 formed on the hub casting 48 will engage the 35 shoulder 51 formed on the locking block 40 and thus force the latch A rearwardly until the pivotal connection 41 is more to one side of the axis of the shaft when the weight of the door and lading will be sufficient to open 40 the door and straighten the linkage. As the weight of the door and lading operate to unwind the shaft, the latter is rotated at great speed but the pawl 62 will ride freely over the ratchet wheel 52 so that the mechanism B and consequently the wrench in the 45 hands of the operator will not be carried in unison therewith but on the contrary will be held steady while the opening movement of the door is being completed. The closing 50 operation of the door is merely a reversal of the opening operation, it being understood that the operator first brings the pawl 63 into engagement with a ratchet wheel 52 and positions the pawl 62 as shown in full 55 lines in Fig. 2.

Referring next to the construction illustrated in Figs. 8 and 9, the arrangement is identical with that hereinbefore described except that a chain 100 is used instead of 60 linked arrangement, said chain winding on

a drum 101 rigidly secured on a shaft 102, the connection between the latch 103 and the chain 100 being effected by means of an eye-bolt 104. Teeth 105 are provided on the drum 101 adapted to have cooperating engagement with teeth 106 formed on the latch 103 and whereby the latch is moved in the housing. 70

Although I have shown and described herein what I now consider preferred embodiments of the invention, the same are merely illustrative, and I contemplate all changes and modifications that come within the scope of the claims appended hereto. 75

I claim:

1. In an operating mechanism for a pivoted car door, the combination with an operating shaft rotatably mounted adjacent the front edge of the door; a movable latch element carried by the door; a stationary anti-friction bearing element supported from the door and adapted to co-act with one end of said latch element; a bodily movable anti-friction element interposed between said shaft and door and spaced relatively to said first named anti-friction element; and operative connections between said shaft and latch element. 80

2. In an operating mechanism for a pivoted car door, the combination with a rotatable winding shaft disposed adjacent the free edge of the door; of a latch element slidably mounted on the door and adapted to engage over said shaft to support the door when closed; means adapted to be wound upon said shaft, operatively connecting the latter with the latch element; anti-friction bearing means for slidably mounting the latch on the door, including a traveling anti-friction element interposed between the door and latch and an anti-friction roller element journaled on the door, supporting and co-operating with one end of said element. 95

3. In an operating mechanism for a pivoted door, the combination with an operating shaft mounted adjacent the free edge of the door; of a latch co-acting with said shaft and operatively connected thereto; means for slidably guiding said latch including a channel member having the web portion thereof secured to the door and the flanges outstanding therefrom, said latch being guided between said flanges; and means for supporting said latch member between said flanges. 105

4. In a railway car the combination with the side wall of the car; of a door hinged on an axis extending at right angles to the side wall of the car; an extension on the side wall of the car depending below the plane of the door; a bottom chord having a horizontally extending flange forming the lower margin of the said side wall; a shaft disposed adjacent the free edge of the door and 110

beneath the side wall; a bearing secured to the bottom chord of the side and within which the shaft is mounted, said bearing being secured to and disposed beneath the 5 said horizontal flange of the bottom chord; shaft rotating mechanism disposed outside of the car wall; and means operatively connecting the shaft to the door.

5. In an operating mechanism for a 10 pivoted car door, the combination with an operating shaft mounted adjacent the free edge of the door; of a latch co-acting with said shaft and operatively connected thereto; means for slidably guiding said latch, including a channel member in the form of a 15 door brace extending across the door and connected to the hinge strap, said member having the web portion thereof secured to the door and the flanges outstanding therefrom, said latch being guided between said flanges; and means for supporting said latch member between said flanges.

6. In an operating mechanism for a 20 pivoted car door, the combination with a 25 rotatable winding shaft disposed adjacent the free edge of the door; of a latch element slidably mounted on the door adapted to engage over said shaft to support the door when in closed position; anti-friction bearing 30 means adapted to support the latch at a point remote from the shaft; a travelling anti-friction element interposed between the

door and latch intermediate the ends of the latch, said element being movable relatively to the door and latch; and a connection 35 adapted to be wound upon said shaft and operatively connecting the latter with the latch element, said connection being adapted to operate as a compression member to displace the latch from its position on the 40 shaft.

7. In an operating mechanism for a pivoted car door, the combination with a 45 rotatable winding shaft disposed adjacent the free edge of the door; of a latch element slidably mounted on the door and adapted to engage over said shaft to support the door when closed; a connection adapted to be wound upon said shaft and having a terminal link operatively connected with the latch, said terminal link being adapted to be locked relatively to the shaft and operate to move the latch in either direction; and a travelling anti-friction element interposed between the door and latch, 50 said element being movable relatively to both the latch and the door.

In witness that I claim the foregoing I have hereunto subscribed my name this 29th day of January 1924.

ARGYLE CAMPBELL.
